UNITED STATES PATENT OFFICE

FRANK VUCHETICH, OF DETROIT, MICHIGAN

WINDOW SCREEN

Application filed May 25, 1931. Serial No. 539,727.

The present invention pertains to a novel window screen, having particular reference to that class of window screen which may be adjusted to fit windows of various sizes.

The primary object of the present invention is to devise a window screen and supporting mechanism that permits the same screen to be used on different windows that vary both as to height and width, the screen being capable of rolling itself into an enclosing casing when such is desired so that access may be had through the window. The present screen includes a telescopic roller around which the screen is rolled by a coiled spring mechanism contained therein and an enclosing casing which is also telescopic. The screen proper is woven in a manner so that it may be expanded or contracted and is secured at its sides adjacent the ends of the telescopic rollers so that a screen is provided that may be varied in width. A screw mechanism is provided within the rollers to positively lengthen or shorten the same along with the telescopic enclosing casing, the screw also serving to hold the screen in any position of adjustment.

With the above and other ends in view the invention consists in matter hereinafter set forth and more particularly pointed out in the appended claims, reference being had to the accompanying drawing, in which

Figure 1 is a front elevation of the screen with the supporting mechanism therefor broken away and in cross section;

Fig. 2 is a transverse cross sectional view taken along the line 2-2 of Fig. 1;

Fig. 3 is a transverse cross sectional view taken along the line 3-3 of Fig. 1, and

Fig. 4 is an enlarged front elevation of a fragment of the screen.

Like characters of reference are employed throughout to designate corresponding parts.

The numeral 1 indicates a bracket that is secured to a window frame or to the wall adjacent a window and secured thereto is a casing member 2 which is substantially semi-circular in cross section as illustrated in Fig. 2. At the opposite end is secured a similar bracket 3 having a similar casing member 4 of a size permitting it to be slipped

into the casing member 2. The casing member 2 is bent over the edges of the casing member 4 as illustrated at 5 in a manner to prevent movement of the two casing members relative to each other in any direction except longitudinally and in this manner the two casing members are telescopically mounted one within the other.

An elongated screw 6 is rotatably mounted in the bracket 1 as at 7, the outer end of the screw being provided with a flat portion 8 that extends outside the bracket 1 and this flat portion is engaged by a plate 9 that is secured to the outside face of the bracket 2 to prevent rotation of the screw. The plate 9 is preferably secured to the bracket by means of screws so that it may be readily removed to permit rotation of the screw when such is desired.

Mounted on the screw 6 so that the latter may freely rotate is a ring 10 and a tube 11 has its end secured on this ring by screws 12. Projecting into the opposite end of the tube 11 is a tube 13 having a ring 14 secured in its outer end. In the inner end of the tube 13 is mounted a bearing ring 15 that has a groove 16 formed therein which receives a ring 17 that is attached to the tube 13 by screws 18 and in this manner the ring 15 is free to rotate relative to the tube 13. A hollow stem 19 has one end mounted in the ring 15 and its opposite end rotatably mounted in the ring 14 and the bracket 3, the outer extremity of the hollow stem being formed with a flat portion 20 that is engaged by a plate 21 to prevent its rotation, the plate 21 being secured to the outer face of the bracket 3 preferably by screws so that it may be readily removed to permit rotation of the stem 19.

The hollow stem 19 receives the end of the screw 6 and is provided with a screwthreaded portion 22 that engages said screw so that rotation of the screw causes the parts to be telescoped in a manner to be presently described.

The ring 14 is secured in the end of the tube 13 by screws 23 and is formed with a lug 24 to which is attached one end of a coiled spring 25, the opposite end of the coiled

spring being attached to a lug 26 formed on the ring 15. The spring serves to re-roll the screen that is mounted upon the tubes 11 and 13 in a manner to be described in a later part 5 of the description.

A wire mesh screen 27 is formed with vertical strands 27' around which are looped angularly extending strands 28 so that the screen may be contracted or expanded. This 10 feature is illustrated in Fig. 4 where the strands are shown distended to their maximum width and it is obvious that the manner in which the strands 28 are woven permits the strands 27' to be moved closer together if such should be desired.

The screen is formed with a comparatively close mesh adjacent each side as at 29 and screws 30 are passed through this portion of the screen into the tubes 11 and 13 to secure 20 the screen thereto. It will be noted however, that a telescopic shield is mounted over the screen at the point of attachment to extend over the entire length of the tubes 11 and 13, the shield 31 also being attached by the 25 screws 31'.

The bottom of the screen is received in telescopic guide members which are illustrated in cross section in Fig. 3 and comprise a member 32 having a substantially tubular form at its bottom to receive a similarly shaped member 33. The member 32 has an internally 30 screw threaded stem 34 rigidly secured therein which receives the screw 35 that is rotatably mounted in the member 33 and rotation of the screw causes the parts 32 and 33 to be telescoped to a lesser or greater length, the screw having a flattened portion 35'.

The outside member 32 is provided with a series of holes 36 and the inside member 33 40 is provided with a series of slots 37 and screws are passed through certain of said holes and slots to clamp the upper parts of the members around the lower end of the screen 27 and to retain it therein and prevent longitudinal 45 movement of the members 32 and 33 relative to each other.

In adjusting the present screen to permit its installation into a window the plate 9 is removed and a suitable tool, such as a crank, 50 is slipped onto the flat portion 8 of the screw 6 which is then rotated so that it is either screwed into or out of the stem 19. If it is screwed in, the tubes 11 and 13 are removed from the brackets 1 and 3 the screw may still 55 be rotated to lengthen them or shorten them for the tube 11 is provided with a longitudinally extending slot 39 into which extends a pin or screw 40 that is secured in the tube 13. This pin and slot serves two purposes, to 60 prevent rotation of the tubes 11 and 13 relative to each other and to prevent the tube 13 from sliding all the way out of the tube 11.

When the tubes 11 and 13 have been adjusted to their proper width the crank may be 65 slipped onto the flat portion 35' of the screw

35 and the latter is rotated so that it co-acts with the tube 34 in forcing the members 32 and 33 the required distance apart.

The shade is adjusted to suit the height of the window by unrolling it from the tubes 11 and 13 and securing the members 32 and 33 at the bottom of the window. Unrolling the screen causes the spring 25 to be wound up in the same manner as a window shade roller so that when the lower end of the screen is released the spring will cause the tubes 11 and 13 to rotate and wind the screen around the same. 70 75

Although a specific embodiment of the present invention has been illustrated and described it is to be understood that various changes may be made in the details of construction without departing from the spirit of the invention as set forth in the appended claims, and such changes are contemplated. 80 85

What I claim is:

1. A device of the character described comprising a pair of tubes telescoped one within the other, an internally threaded stem secured within said tubes, a screw rotatably mounted within the other of said tubes and having its end received within said stem, and an expansible window screen having its opposite edges attached to opposite tubes and adapted to be rolled around the same. 90 95

2. A device of the character described comprising a pair of tubes telescoped one within the other, an internally screwthreaded stem secured in one of said tubes and having a portion projecting outwardly therefrom, a screw rotatably mounted in the other of said tubes and received in said stem and having a portion extending outwardly from the end of said tube, a section of casing receiving the outwardly projecting portion of said stem, a section of casing receiving the outwardly projecting portion on said screw, one of said casing sections being bent to receive the other in a manner to permit telescoping thereof, and an expansible screen having its opposite edges secured to opposite tubes and adapted to roll around the same. 100 105 110

3. A device of the character described comprising a pair of tubes telescoped one within the other, a longitudinally extending slot formed in one of said tubes, a pin secured in the other of said tubes and received in said slot, an internally threaded stem secured within said tubes, a screw rotatably mounted within the other of said tubes and having its end received within said stem, and an expansible window screen having its opposite edges attached to opposite tubes and adapted to be rolled around the same. 115 120

4. A device of the character described comprising a pair of tubes telescoped one within the other, an internally screwthreaded stem secured in one of said tubes and having a portion projecting outwardly therefrom, a screw rotatably mounted in the other of said 125 130

tubes and received in said stem and having a portion extending outwardly from the end of said tube, a section of casing receiving the outwardly projecting portion of said stem, a 5 section of casing receiving the outwardly projecting portion on said screw, one of said casing sections being bent to receive the other in a manner to permit telescoping thereof, an expansible screen having its opposite edges 10 secured to opposite tubes and adapted to roll around the same, telescoping members having the lower end of said screen secured thereto, and a screw mechanism for causing telescopic movement of said members.

15 5. A device of the character described comprising a pair of tubes telescoped one within the other, an internally threaded stem secured within one of said tubes, a screw rotatably mounted within the other of said 20 tubes and having its end received within said stem, an expansible window screen having its opposite edges attached to opposite tubes and adapted to be rolled around the same, and a spring mounted in one of said tubes and 25 adapted to automatically cause said screen to be rolled around said tubes.

6. A device of the character described comprising a pair of tubes telescoped one within the other, an internally screwthreaded 30 stem secured in one of said tubes and having a portion projecting outwardly therefrom, a screw rotatably mounted in the other of said tubes and received in said stem and having a portion extending outwardly from the end of 35 said tube, a section of casing receiving the outwardly projecting portion of said stem, a section of casing receiving the outwardly projecting portion on said screw, one of said casing sections being bent to receive the 40 other in a manner to permit telescoping thereof, an expansible screen having its opposite edges secured to opposite tubes and adapted to roll around the same, and a spring mounted in one of said tubes and adapted to automatically cause said screen to be rolled around 45 said tubes.

7. An expansible screen roller comprising a pair of tubes telescoped one within the other and adapted to have a screen rolled around 50 the same, an internally threaded stem secured in one of said tubes, a screw rotatably mounted in the other of said tubes and having its inner end received in said stem, and means for preventing rotation of said tubes relative to each other.

8. An expansible screen roller comprising a pair of tubes telescoped one within the other and adapted to have a screen rolled around the same, an internally screwthreaded stem 60 secured in one of said tubes and having a portion extending outwardly from the end thereof and adapted to be received in a supporting bracket, a screw rotatably mounted in the other of said tubes and having its inner end received in said stem and its opposite

end projecting outwardly beyond the end of said tube and adapted to be received in a supporting bracket, and means for preventing rotation of said tubes relative to each other.

In testimony whereof I affix my signature. 70
FRANK VUCHETICH.
